UNITED STATES PATENT OFFICE.

SAMSON D. WRIGHT, OF CLEVELAND HEIGHTS, OHIO.

RECORDING SCALE FOR RAILWAY CARS.

Application filed October 16, 1922. Serial No. 594,853.

This invention relates to an improved recording scale for railway cars.

The present invention is an improvement upon the device disclosed in my Patent No. 1,329,567 of February 3, 1920, to which reference may be had for a fuller understanding of the present structure.

Broadly considered, the present invention comprises an indicating and recording mechanism mounted upon a stationary part of a railway car, as for instance the car frame, and having operative connection with the body of the car into which the materials are loaded so as to be responsive to the loads placed in the car. With this device it is possible to obtain a visual reading of the aggregate load in the car from time to time and also to obtain a permanent record in the form of a sheet which is perforated by means of a stylus or marked by any other suitable form of such device, which is actuated together with the indicator through operative connections from the body of the car.

The objects of the present invention are to provide improved means for maintaining in proper operative position the rack which actuates the pinion on the shaft of the indicating finger; to provide means for limiting the movement of the indicator so as to prevent negative readings of the same; to provide a telescopic sleeve for the dash pot which forms a part of the indicating mechanism; to provide readily removable dust excluding means for the bottom part of the frame within which the mechanism is mounted; to provide housings for the ball bearings of the indicator shaft and the tractor shaft, so as to permit these parts to be installed as assembled units; and finally to provide an improved brake means for the tape feeding mechanism so as to prevent undue movement of the same.

Other objects of this invention will appear from the following description and claims when considered in connection with the drawings.

Fig. 1 is a front elevation of my improved device with the front wall of the casing removed and with parts broken away; Fig. 1^a is a detail sectional view on line 1^a—1^a of Fig. 1 showing the guide pins for the rack; Fig. 2 is a side elevation taken from the left of Fig. 1; Fig. 3 is a side elevation taken from the right of Fig. 1, with the wall of the casing removed; Fig. 4 is a

plan view of my device; Fig. 5 is a detail view of part of the mechanism as shown in Fig. 3; Fig. 6 is an enlarged detail plan view similar to Fig. 4; Figs. 7 and 8 are sectional detail views of the housings for the shafts of the indicator and the tractor wheel; Figs. 9 and 10 are detail views of the record cutter; Fig. 11 is a detail view of the actuating means for the record feeding device; and Fig. 12 is a detail view.

Within the casing 1, which is suitably mounted upon the stationary frame of a car, there is pivoted at the point 2 the lever 3 which has pivotal connection at 4 with a depending rod 5 suitably connected with the body of the car for actuation thereby upon placing loads within the car. The other end of the lever 3 has pivotal connection at the point 6 with the rod 7 which constitutes part of the dash pot indicated in a general way by reference numeral 8. The tubular sleeve 9 is suitably secured within the cover 10 of the dash pot and co-operates with the telescoping member 11 which is suitably secured upon the rod 7. This telescopic arrangement prevents oil being pumped out by the piston in the dash pot, and further provides a means of protecting the same against the entrance of dirt. Depending from the bottom of the casing 1, I have provided the projections 12 and 13 at the points where the rods 5 and 7 extend through the frame; and I have mounted upon these extensions in any suitable manner, as for instance by means of the removable wires 14 and 15, the flexible containers 16 and 17 which may be made of canvas or other suitable material for the purpose of excluding dirt or other foreign matter which may find its way down through the bottom of the casing. The bottoms of these members 16 and 17 are drawn in around the rods 5 and 7 and are secured in such position by means of the removable wires as indicated by reference numeral 18.

Suitably pivoted at the point 19 upon the lever 3 is the upwardly extending rod 20 having adjustable connection at the point 21 with the rod 22, the upper part of which is formed as a spiral fin 23 which is adapted for engagement between the coils of the spring 24. This spring depends from the support 25 secured in the upper part of the frame member 26 and constitutes a means of returning the lever 3 together with the other parts of the indicating apparatus to

normal position upon removal of the load from the car body. The rod 27, which has a knife edge pivotal connection at the point 28 with the lever 3, is connected at its upper end to the rack bar 29 which is adapted for vertical movement according to the movement of the lever 3. As a means of preventing undue movement of the rack bar 29 because of any sudden loading of material into the car body, I have provided the angular plate member, one arm 30 of which is secured in position upon the rod 22 between the nuts 31 and 32 by means of the cut out portion 30^a, while the other angular extension 33 is provided with a cut out portion 34 adapted to receive the rack bar 29. The angular portion 33 is adapted for engagement by the shoulder 27^a of the rod 27 so as to prevent undue upward movement of the rack bar 29. In this way the rod 27 is prevented from such upward movement as might result in the entire unseating of the lower portion of the same from the knife edge forming part of its pivotal connection 28. The guide pins 28^a extending across the hollow part of the lever 3 prevent the rod 27 from being displaced laterally from the knife edge.

The rack bar 29 has meshing engagement with the pinion 35 mounted substantially midway of the indicator spindle 36 and is adapted to actuate the same so as to indicate the amount of load placed upon the car body. The spindle 36 is provided with ball bearings 37 and 38 which are adapted to be enclosed within the separable members 39, 39^a and 40, 40^a, which constitute housings for the ball bearings. These members are provided with screw thread engagement, as indicated at 39^b and 40^b, and one of them is provided also with the flange 40^c for engagement with the frame of the device by means of the screw bolts 40^a. With this arrangement the housings can be assembled so as to enclose the ball bearings upon the spindle and then assembled as a unit within the frame of the machine, thereby precluding the possibility of entrance of dirt or other foreign matter in the ball bearings during the assembling operation. This arrangement allows also for expansion and alignment of the parts. The indicating finger 41 is suitably secured upon the front end of the spindle 36 for co-operation with the dial 42 so as to indicate the load placed in the car, and the dial is clearly visible through the glass front 42^a.

I have further provided an attachment to facilitate the reading of the net weight of material loaded into the car when such material is loaded in a bucket or other container. With this arrangement, the scale is so set that the indicator will stand at zero with the empty bucket itself resting on the body 45 of the car. Then when the bucket is filled

and loaded onto the car, the exact weight of the net load can be read directly from the indicator. As a means of preventing the indicating finger from passing beyond zero to show a negative reading upon removal of the bucket, I have provided a stop which comprises the set screw 43 adjustably mounted in the frame and adapted to engage the top part of the lever 3. By this means the indicating finger is prevented from passing to any considerable degree beyond the zero point in a counter-clockwise direction, as viewed in Fig. 1.

As a further means of properly maintaining the rack bar 29 in proper operative engagement with the pinion 35, I have provided the bar 44 which is pivotally mounted at the point 45 in the frame of the mechanism, and which carries the pivotally mounted roller 46 for bearing engagement with the back of the rack bar 29. The upper end of the bar 44 is pivotally connected to the rod 47 which extends through the wall of the frame portion 26 and which is adapted to be set in proper position by means of the nuts 48 and 49 adapted to engage the two sides of the frame wall. This arrangement affords a readily accessible means of adjusting the roller 46 so as to bear with proper pressure upon the rack bar 29 and thus prevent the same from becoming accidentally displaced.

The means for providing a permanent record of the aggregate load upon the car body comprises a flexible tape 50 supplied from the reel 51 and wound upon the separable take-up reel 52 after passing the recording mechanism. This tape passes over the cylinder 53 so as to receive an impression by the stylus 54 arranged directly thereabove. The curved plate 55, one end of which is secured to the cylinder 53 and which can be mounted in the frame of the machine in any suitable manner, determines the path of the tape to the take-up reel 52. The weighted roll 56 mounted upon the arm 57 which in turn is pivotally mounted at the point 58 in the frame of the device, maintains the tape in its proper path so as to pass properly under the stylus 54. This tape is fed forwardly by means of the toothed wheel 59 mounted upon the spindle 60, the teeth of the wheel engaging in perforations in the marginal portions of the tape.

The spindle 60 is provided with ball bearings 61 and 62 which are enclosed within housings comprising the separable members 63, 63^a and 64, 64^a. The structure of these housings is the same as in the case of the indicator spindle already described and clearly illustrated in Figs. 7 and 8. Suitably mounted upon the spindle 60, there is provided the ratchet wheel 65 adapted for co-operation with the pawl 66, which is pivotally mounted at the point 67 upon the

bracket 68 on the armature 69. The armature is pivotally mounted at the point 70 in the frame of the apparatus and is actuated by means of the electro-magnets 71 which are adapted to be energized through a circuit which can be closed either manually or automatically. With this arrangement, it will be seen that upon energization of the magnets the pawl 66 will be lowered, and upon release of the same the pawl will be raised by means of the connection to be later described so as to rotate the ratchet wheel in a clockwise direction as viewed in Fig. 11 and thereby feed the tape.

15 The means for marking the tape comprises the stylus 54 which is mounted upon the end of a spring arm 72, the other end of which is fixedly mounted upon one stretch of the endless tape or belt 73 extending about the 20 rollers 74, 75 and 76. The end rollers 74 and 76 are merely idlers while the other roller 75, which is fixed upon the spindle 36, is provided with teeth for engagement in holes in the tape 73. Thus, the tape 73 will be 25 moved back and forth according to the movement of the indicating finger 41, which is fixed upon the spindle 36. In other words, the position of the stylus 54 with respect to the width of the record tape will correspond 30 to the load placed upon the car body. The stylus 54 is adapted to work back and forth in a suitably formed groove or way 77 formed as a part of the frame 78 which is pivotally mounted at the points 79 and 80 35 upon the main frame of the machine structure by means of the adjustable screws 81 and 82. The pivoted frame 78 is provided at its one end portion with the extending arm 83 which is suitably apertured so as to 40 permit the extension therethrough of the screw threaded upwardly extending rods 84 and 85. The rod 84 is pivotally mounted at its lower end to the bracket 86 suitably secured upon the armature 69, and extends 45 also through the stationary extensions 87 and 88 formed upon the frame of the machine. The spring 89 is arranged about the rod 84 and has abutment between the arm 83 and the extension 88. Another coil spring 50 90 abuts at its upper end against the adjustable lock nuts 91, and at its lower end against the angular portion 92 of a brake arm to be later referred to. The rod 85 is provided with the stop nuts 93 and 94 located above 55 and below the arm 83, while the lower end of the rod 85 has pivotal connection at the point 95 with the armature 69. The brake arm before referred to is pivotally mounted at the point 96 to the frame of the machine 60 and is provided with a brake shoe 97 adapted for engagement with the drum portion 98 formed as part of the ratchet 65 so as to control the movement of the feed drum.

Thus it will be seen that according to the 65 weight of the load placed in the car, the in-

dicating finger will be actuated and the stylus will be moved to a certain position across the record tape; and then upon energization of the electro-magnets, the engagement of nuts 93 with the arm 83 will cause depression of stylus 54 so as to impress the record tape and thereby indicate the amount of the load. At the same time, rod 84 will be lowered through its connection with the armature, and nuts 91 engaging spring 90 will place tension upon the brake arm so as to prevent rotation of the feed drum during the recording operation. Then, upon de-energization of the electro-magnets, the pawl 66 will be released so as to engage the ratchet 80 and move the same in a clockwise direction so as to feed the paper forwardly, this operation taking place immediately after the stylus 54 has returned to its inactive position by means of the spring 89 forcing the bar 83 upwardly. At all times, there is sufficient tension upon the spring 90 to prevent overrunning or undue feeding movement of the feed drum.

The take-up reel may be omitted entirely, in which case the feed tape will be permitted to collect in the bottom of the casing and removed from time to time as may be desired, as for instance, at the end of the day, and the back of the casing may be made removable for this purpose. The tape is torn off by means of cutting blade 99 which is provided with the flexible ears 100 for engagement in the annular groove 101 provided upon each of set screws 102. The set screws 100 engage also the frame of the machine and are adapted upon turning the same to adjust the position of the cutting blade.

What I claim is:

1. In a recording scale for railway cars, the combination of a frame, a lever pivotally mounted in said frame and responsive to the load on a car, a rack bar having pivotal connection with said lever, a pinion meshing with said rack for operation thereby, an indicator operated by said pinion, a bar adjustably mounted in the frame, a pressure roller mounted on said bar and adapted to bear against said rack bar to maintain the same in mesh with said pinion, and means extending to the outside of said frame for adjusting said bar.

2. In a recording scale for railway cars, the combination of a frame, a lever pivotally mounted in said frame and responsive to the load on a car, a rack bar having pivotal connection with said lever, a pinion meshing with said rack for operation thereby, an indicator operated by said pinion, a bar pivotally mounted in the frame, a presser roller mounted on said bar and adapted to bear against said rack bar to maintain the same in mesh with said pinion, and means extending through said frame and connected with the free end portion of said bar for ad-

justment of the same from a point outside of the frame.

3. In a recording scale for railway cars, the combination of a frame, a lever pivotally mounted in said frame and responsive to the load on a car, a knife edge on said lever, a rack bar having a bearing for engagement upon said knife edge, a pinion meshing with said rack for operation thereby, an indicator operated by said pinion, and means for maintaining said rack bar in operative relation to said knife edge.

4. In a recording scale for railway cars, the combination of a frame, a lever pivotally mounted in said frame and responsive to the load on a car, a knife edge on said lever, a rack bar having a bearing for engagement upon said knife edge, a pinion meshing with said rack for operation thereby, an indicator operated by said pinion, and means for preventing accidental dislodgement of said rack bar from operative relation with said knife edge.

5. In a recording scale for railway cars, the combination of a frame, a lever pivotally mounted in said frame and responsive to the load on a car, a knife edge on said lever, a rack bar having a bearing for engagement upon said knife edge, a pinion meshing with said rack for operation thereby, an indicator operated by said pinion, and means for limiting the longitudinal movement of said rack bar so as to preserve the operative relation between said knife edge and the bearing on said rack bar.

6. In a recording scale for railway cars, the combination of a frame, a lever pivotally mounted in said frame and responsive to the load on a car, a spring having one end anchored to said frame, a rod connecting the other end of said spring to said lever, a knife edge on said lever, a rack bar having a bearing for engagement upon said knife edge, a pinion meshing with said rack for operation thereby, an indicator operated by said pinion, said rod and rack bar extending in substantially parallel relation, and means carried by said rod and being operatively associated with said rack bar for engagement thereby so as to prevent undue longitudinal thrust of said rack bar.

7. In a recording scale for railway cars, the combination of a frame, means mounted on said frame and having movement responsive to the load on a car, a record sheet, a stylus automatically adjustable across said sheet according to the movement of said means, means for feeding said sheet and causing said stylus to impress said sheet to record the weight of a given load, and a brake for said feeding means to prevent undue feeding of the record sheet.

8. In a recording scale for railway cars,

the combination of a record sheet, means for recording upon said sheet the load on a car, means for advancing said sheet and actuating said recording means, and a brake operatively associated with said last named means for preventing undue feeding of the sheet.

9. In a recording scale for railway cars, the combination of a record sheet, means for recording upon said sheet the load on a car, means including pawl and ratchet mechanism for advancing said sheet, and a brake means operatively associated with said last named means for preventing undue rotation of said ratchet.

10. In a recording scale for railway cars, the combination of a record sheet, means for recording upon said sheet the load on a car, a pawl and ratchet mechanism for feeding said sheet, said ratchet having a drum, a pivotally mounted arm, a brake shoe carried by said arm, spring means for effecting engagement of said shoe with said drum, and means for marking and advancing said sheet, said last named means being operatively associated with said brake arm so as to prevent accidental rotation of said ratchet during the marking operation.

11. In a recording scale for railway cars, the combination of a frame provided with a pair of aligned openings, a dial associated with said frame, a shaft rotatably mounted in said openings, a pointer carried by said shaft for cooperation with said dial, and spaced anti-friction structures carried by said shaft and adapted to be arranged within said frame openings upon endwise movement of said shaft, whereby said shaft and said anti-friction structures may be assembled with and disassembled from said frame as a unit.

12. In a recording scale for railway cars, the combination of a frame provided with a pair of aligned openings, a dial associated with said frame, a shaft rotatably mounted in said openings, a pointer carried by said shaft for cooperation with said dial, and spaced anti-friction structures carried by said shaft and adapted to be arranged within said frame openings upon endwise movement of said shaft, said anti-friction structures each including ball bearings and a housing enclosing the same, whereby said shaft and said anti-friction structures may be assembled with and disassembled from said frame as a unit, the housing of one of said anti-friction structures being provided with means for securement to said frame adjacent one of the aligned openings therein.

In testimony whereof I hereby affix my signature.

SAMSON D. WRIGHT.
